UNITED STATES PATENT OFFICE.

MARIUS LETH, OF OMAHA, NEBRASKA.

GARMENT SUPPORT AND STRETCHER.

1,343,397.

Specification of Letters Patent. Patented June 15, 1920.

Application filed January 12, 1920. Serial No. 350,898.

To all whom it may concern:

Be it known that I, MARIUS LETH, a citizen of the United States, residing at Omaha, in the county of Douglas and State of Nebraska, have invented certain new and useful 5 Improvements in Garment Supports and Stretchers, of which the following is a specification.

The present invention relates to garment supports and stretchers, and has more particular reference to an improvement in a device for suspending and holding in a creased and flattened condition the legs of trousers.

The object of the present invention is to 10 provide a relatively light, strong, durable and quickly applied stretcher for application to trousers to hold the same in a stretched flat condition for maintaining the crease therein and to afford means for suspending 15 the garment from a hook or the like conveniently placed in a closet or in a wall.

Another object of this invention is to provide a stretcher which is made substantially in one piece, which is resilient to an extent sufficient for wedging or binding in the garment, and which is in the form of a wedge 25 for binding the device within the garment by slipping the reduced end therein and drawing the device through the garment to the desired extent.

The above, and various other objects and advantages of this invention will in part be described in, and in part be understood from, the following detailed description of 30 the present preferred embodiment, the same being illustrated in the accompanying drawing, wherein:

Figure 1 is a side elevation of a garment stretcher constructed according to the present invention and as applied to a trouser leg, the latter being shown in section.

Fig. 2 is an edge elevation of one end of the device, shown on an enlarged scale.

Fig. 3 is an enlarged transverse section 45 taken on the line 3-3 of Fig. 2.

Referring to the drawing, the garment stretcher and support comprises a pair of side bars 10 and 11 preferably constructed of relatively thin sheet metal and being relatively straight throughout the major portions of their lengths and reinforced against bending and buckling by ribs 12 which are pressed outwardly and longitudinally from the bars 10 and 11.

50 At each end of the device the bars 10 and

11 are connected together by spring means. One end of the device, which may be termed the inner end, is provided with a coil spring 13 and the other or outer end of the device is provided with a second coil spring 14. 60 These springs 13 and 14 are preferably of spring steel and composed each of one helix, and have the helices terminating in crossed diverging arms 15 which are flattened and are brazed, welded or otherwise suitably secured to the side bars 10 and 11 to form, substantially, continuations thereof. 65

It will thus be seen that the side bars 10 and 11 are yieldingly connected together at opposite ends and that the side bars are 70 urged apart by the crossed arms 15 of the springs to force the remote edges of the side bars 10 and 11 into the creases of the garment for holding such creases across the edges of the side bars and drawing taut the portions 75 of the garment at opposite sides of the creases.

Another feature of this invention is in providing a relatively wider or larger spring device 13 at the inner end of the stretcher 80 than the spring device 14 at the outer end thereof. This is accomplished, preferably by making the arms 15 of the spring 13 longer than the corresponding arms of the spring 14. The result is that the stretcher is of wedge 85 shape, tapering toward its outer end so that said end may be inserted in the garment and drawn through the same until the side bars 10 and 11 are compressed to the desired tension for stretching and holding the garment. 90 It will further be noted that the springs 13 and 14 extend longitudinally outward from the ends of the stretcher to serve not only as finger holds for facilitating positioning and removal of the device, but also to serve 95 as loops or rings for engagement over hooks upon which the stretcher may be suspended.

From Fig. 2, particularly, it will be noted that the arms 15 of the springs are not only flat where they merge into the ends of the 100 side bars 10 and 11, but that they also curve edgewise inwardly toward each other and may be sufficiently spaced apart at their crossed portions to admit free flexing or bending of the springs 13 and 14 during compression and expansion of the ends of the 105 stretcher.

A stretcher is therefore provided which is made substantially in one piece, which presents relatively sharp or thin edges to the 110

creases of the garment, which is relatively flat to prevent undue bulging of the garment within which the stretcher may be placed, and a stretcher which may be drawn into and out of the garment with relative ease. Further, the springs 13 and 14 with their arms 15 are so arranged and connected to the side bars 10 and 11 as to effect, upon the initial drawing of the stretcher into and out of the garment, a contraction of the side bars 10 and 11 which facilitates the movement of the stretcher into and out of position. As the stretcher requires no adjustment or interfitting of parts, it may be quickly inserted at its reduced end into a garment and is preferably pulled into the contracted end of the garment for drawing the latter taut and obtaining the desired tension of the stretcher on the garment.

It is of course understood that various modifications and changes may be made in the details of construction and design of the above specifically described embodiment of this invention without departing from the

spirit thereof, and limited only by the scope 25 of the following claim.

What is claimed is:—

A one-piece garment stretcher comprising a pair of spaced-apart bars having pressed-up reinforcing ribs converging upwardly, 30 said bars adapted to fit edgewise within a garment, curved arms at the upper ends of the bars crossing each other and looped to provide a coil spring serving to force the arms yieldingly apart, curved arms on the lower wider ends of the bars crossing each other and looped downwardly to provide a coil spring for resiliently spreading the bars at their lower ends, said loops adapted to form finger holds at the upper and lower 35 40 ends of the stretcher.

In testimony whereof, I have affixed my signature in presence of two witnesses.

MARIUS LETH.
